US00D850018S

(12) **United States Design Patent** (10) **Patent No.:** **US D850,018 S**
Paxson (45) **Date of Patent:** **** May 28, 2019**

(54) **PET FOUNTAIN**

(71) Applicant: **Doskocil Manufacturing Company, Inc.**, Arlington, TX (US)

(72) Inventor: **Ryan Paxson**, Box Elder, SD (US)

(73) Assignee: **DOSKOCIL MANUFACTURING COMPANY, INC.**, Arlington, TX (US)

(**) Term: **15 Years**

(21) Appl. No.: **29/619,966**

(22) Filed: **Oct. 3, 2017**

(51) LOC (11) Cl. **30-03**

(52) U.S. Cl.

USPC **D30/132**

(58) **Field of Classification Search**

(57) **CLAIM**

The ornamental design for a pet fountain, as shown and described.

DESCRIPTION

FIG. 1 is a front perspective view of a pet fountain in accordance with my new design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is a cross-sectional view of a lower portion of the pet fountain.

The broken lines depict environmental subject matter, are for illustration only, and form no part of the claimed design.

1 Claim, 8 Drawing Sheets
